JOSEPH HAWKINS, OF WEST WINDSOR, NEW JERSEY.

Letters Patent No. 64,765, dated May 14, 1867.

IMPROVEMENT IN HINGED GUN-REST.

The Schedule referred to in these Letters Patent and making part of the same.

TO ALL WHOM IT MAY CONCERN:

Be it known that I, JOSEPH HAWKINS, of West Windsor, New Jersey, have invented certain improvements in Fire-Arms; and I do hereby declare the following to be a full, clear, and exact description of the same, reference being had to the accompanying drawing, and to the letters of reference marked thereon.

My invention consists in a jointed rod connected to a plate sliding beneath the barrel of a fire-arm, so as to be either folded close to the latter, or turned down to form a rest for the forward end of the piece; and my invention further consists in a spring-catch arranged as described hereafter, for securing the bayonet to the barrel.

In order to enable others skilled in the art to make and use my invention, I will now proceed to describe its construction and operation. On reference to the accompanying drawing, which forms a part of this specification—

Figure 1 is a longitudinal section of a rifle showing my improvement.

Figure 2, a section on the line 1-2, fig. 1, drawn to an enlarged scale.

Figures 3, 4, and 5, detached sectional views of parts of the fire-arm drawn to an enlarged scale.

A is the stock, and B the barrel of the fire-arm, which is provided with a hammer and the usual lock and trigger for operating the same. The under side of the barrel B is of such increased thickness as to admit of an opening being made for the reception of the ramrod, C, and to a plate, D, which is secured to the under side of the barrel, and extends the entire length of the same, is adapted a slide, F, to the under side of which is jointed one end of a rod, G, the latter being divided into two lengths, *a* and *b*, hinged together at *x*, and on the rod is a slide H, by means of which the sections may be held together when the rod is folded, as shown in fig. 1. At the under side of the barrel, near the rear end of the same, slides a plate, I, from the forward edge of which projects a lip, *e*, a spring, *i*, tending to maintain the plate at the limit of its forward motion. The socket J of a bayonet is adapted to the end of the barrel, and in the plate D, near the muzzle, is a spring-catch *n* with an inclined end and an abrupt shoulder, the latter (when the bayonet is in its place on the barrel) projecting beyond the edge of the socket, and retaining the latter in its place. When the fire-arm is not required for use, the section *l* of the rod G is folded against the upper section *a*, and is secured by the slide H, the slide F is brought to the front end of the barrel, the plate I is withdrawn, and the bar G is folded against the barrel, as shown in fig. 1, when the plate I is moved forward so that its lip *e* shall underlap the end of the section *a*, and retain the bar in its position. When it is desired to use the piece, the plate I is withdrawn so as to release the bar G, and the latter is turned down to the position shown in red lines, fig. 1, the lower end bearing on the ground, and the bar thus forming a steady rest for the forward portion of the piece. When the operator is behind a bank, or in a kneeling position, the bar G may be shortened by folding the section *l* against the section *a*, so that the end of the latter may bear on the ground; the slide F may also be moved along the plate D to any desired position beneath the barrel. When the bayonet has to be removed the end of the catch *n* is pressed upwards towards the barrel until the shoulder of the catch is removed from the edge of the socket J, when the latter may be readily slipped from its place.

It will be apparent that this device may be applied to muskets, carbines, shot-guns, or rifles.

I claim as my invention, and desire to secure by Letters Patent—

The slide F and jointed rod G, in combination with a plate, D, beneath the barrel B of a fire-arm, the whole being constructed and arranged as described.

In testimony whereof I have signed my name to this specification in the presence of two subscribing witnesses.

JOSEPH HAWKINS.
